UNITED STATES PATENT OFFICE.

HENRY F. W. SEELE, OF ROLLA, MISSOURI.

NEEDLE-THREADER FOR SEWING-MACHINES.

SPECIFICATION forming part of Letters Patent No. 268,551, dated December 5, 1882.

Application filed July 12, 1882. (Model.)

To all whom it may concern:

Be it known that I, HENRY F. W. SEELE, of Rolla, in the county of Phelps and State of Missouri, have invented a new and Improved 5 Needle-Threader Device for Sewing-Machines, of which the following is a full, clear, and exact description.

The object of my invention is to provide 10 sewing-machines with a needle-threading attachment that can be conveniently used whenever required.

Reference is to be had to the accompanying 15 drawings, forming a part of this specification, in which similar letters of reference indicate corresponding parts in both the figures.

Figure 1 is a front elevation of a sewing-machine head with the needle and presser-bars, and having my improved threader attached. Fig. 2 is a side view at right angles 20 to Fig. 1, showing the threader as turned to one side.

The device may be applied to any sewing-machine of ordinary construction.

A in the drawings is the presser-bar of the 25 machine. B is the needle-bar, and a the needle. C is the threader, the same consisting of a metal block formed at one side with a vertical groove, b, for taking upon the needle, and formed transversely in line with the groove b, 30 with a V-shaped or flaring aperture, d, the upper side of which is open or cut out. This threader C is attached upon the end of an arm, e, that is hung by a ring or collar, f, on the presser-bar A, so that the threader may be turned 35 upon the presser-bar in a horizontal direction. The arm e is fitted above the threader C with a cutter, g, for use in cutting the thread, and this cutter may be used in either position of the threader.

To thread the needle it is raised to its highest point, and the threader C then turned around against the needle. The groove b in the threader serves to guide and retain the needle, and in this position the eye of the needle is at the inner end of the flaring aperture d. The thread is to be inserted through the aperture d, and thus guided to the eye of the needle directly. The open upper side of the aperture allows the thread to pass out of the threader. When not required for use the 45 threader is to be turned to one side, as shown in Fig. 2.

This threading device may be hung otherwise than from the presser-bar. I do not limit myself in that respect.

The device is convenient for use, as the hole 55 guiding the thread is well open on top, corresponding with the natural vision of the eye, so that the thread can be applied in the right direction, and for the same reason the device 60 can be utilized for setting the needle.

Having thus described my invention, I claim as new and desire to secure by Letters Patent—

1. A circularly-movable threader, C, having the cutter g rigidly fixed on the upper side of 65 an arm, e, pivoted to and lying between the movable collar f and the threader itself, whereby said cutter can be conveniently used, no matter on which side the threader may be turned.

2. The combination of the threader C, formed with tapering aperture d, the arm e, and collar f, with the presser-bar A, substantially as 70 shown and described.

HENRY FRED. WM. SEELE.
